UNITED STATES PATENT OFFICE.

DANIEL BRUHN, OF HAMMOND, INDIANA.

COAL-CHUTE.

1,146,127.

Specification of Letters Patent.

Patented July 13, 1915.

Application filed June 18, 1914. Serial No. 845,783.

To all whom it may concern:

Be it known that I, DANIEL BRUHN, a citizen of the United States, residing at Hammond, Lake county, Indiana, have invented certain new and useful Improvements in Coal-Chutes, of which the following is a specification.

My invention relates to so called coal chutes which are in the form of an iron frame which is inserted in an opening in a basement wall and is provided with a cover, door or closer which may be opened only from within and which door may also, when desired, contain a heavy glass which makes 15 it serve as a window when not in service as a coal chute.

For practical purposes the questions of simplicity of construction and even a small reduction in cost are important in connection with these structures owing to the quantities of same that are being used.

The objects of the present invention are to reduce the weight, the amount of metal required and the number of parts, and to 25 obviate the use of pivot lugs, friction-parts and the like at comparatively vital points in the construction, so as to make the chute comparatively light in handling and shipment, simple in the matter of installation, 30 and comparatively free from the liability of derangement.

With these objects in view the invention consists in the novel construction, combination and arrangement of parts hereinafter 35 described in detail, illustrated in the accompanying drawing and incorporated in the appended claims.

In the drawing—Figure 1 is a vertical section through the chute and a section of 40 building wall into which the chute has been inserted. Fig. 2 is a similar view showing the door open and is substantially a section taken on line 2—2 of Fig. 3. Fig. 3 is a perspective view of the chute alone, open. Fig. 45 4 is a broken away detail view. Fig. 5 is an enlarged section taken substantially on line 5—5 of Fig. 1.

In the several views 2 represents the wall 50 of a building in which has been made an opening 3 for the reception of the chute which consists of a rectangular, box-like frame 4 having flanges 5, 6, 7 and 8 which

serve as a frame around the chute-opening as seen from the outside of the building. In the front portion of this opening or of 55 the frame 4 is pivoted the door 9, to which are riveted segmental plates 10 and 11 which form sides for that portion of the chute which projects beyond the exterior of the building when the chute is open as in Figs. 60 2 and 3.

As shown in Fig. 1 the door 9, when closed, is arranged to be within the vertical plane of the wall and of the opening frame consisting of the flanges 5, 6, 7 and 8, 65 which prevents water running down the outer face of the wall from entering within the chute. At the lower side of the opening under the door the frame portion 6 is provided with an inclined sill portion 12 which is formed with an upward bulge, ridge or bead 13 which extends above the lower edge of the door at its rear side and serves to prevent water running down the door from entering the inclined chute portion 14 of 70 the frame 4. At its lower edge the door 9 is provided with a stiffening rib 15 the ends of which are bent over to form substantially round trunnions 16 and 17 which are journaled in openings 18 and 19 in the sides of 80 the frame 4, said rib 15, as shown in Fig. 4, being half round in cross section and riveted to the door. A simple form of wall shield that is inexpensive and mounted to insure 85 strength and permanency is provided in a plain rectangular plate of metal which is formed with lugs bent into loops or eyes 21 and 22 that rotatably engage a fixed rod 23 riveted at its ends 24 and 25 into bores in the sides 10 and 11 into which said ends fit 90 snugly. This plain rod mounted in this fixed manner obviates the usual unstable mountings for these shields and obviates the need of special dies and parts which are not 95 stable market articles. Another function of the rod 23 is to support the sides 10 and 11 against pressure of coal thrown against them which would tend to bend or crowd them against the sides of the frame 4 and make it troublesome to open and close the door. The 100 free edge of the shield 20, when the latter is in closed position, rests upon a pair of studs 26 and 27 secured to the sides 10 and 11, but even if these studs should accidentally be

broken off that would not in the least incapacitate or disarrange the chute for working purposes, the construction being designed throughout to obviate liability to accidental 5 breakage in any of the vital parts such as the mounting of the door, its pivotal supports and the pivotal supports for the shield 20 designed to protect the wall of the building when coal is thrown into the chute. The 10 lug or pin 27 is also used as a part of a simple latch arrangement for locking the door shut against being opened from the outside. On one of the vertical sides of the frame 4 is secured in any suitable manner, 15 as by rivets 28 and 29, a bearing bar 30 on which is pivoted or fulcrumed at 31 a lever or handle 32 in which is formed a notch 33 adapted to engage the pin or stud 27 the moment the door is in its vertical or closed 20 position as in Fig. 1. This lever is provided with an incline or beveled portion 34' against which a stud 34 strikes in its rearward movement, thus raising the handle or lever so that it may be engaged with said pin. The 25 release to open the door is effected by simply raising the handle and pushing against the door from its rear or inside.

From the outer face of each side 10 and 11 projects a stud 34 for which there is 30 room between said sides and the ends of the frame 4 to substantially the extent of the thickness shown in Fig. 5 of a narrow in-turned flange 35 formed on each of the flanges 7 and 8. This flange 35 is in each 35 instance secured to 4 in Fig. 5, and side views of it are shown by dotted lines in Figs. 1 and 3 and partly in full lines in Figs. 2 and 4. The vertical edges where the leader lines from 35, 35 in Fig. 5 strike 40 also constitute stops for the stud or pin 34, thus simplifying the construction by doing away with special parts for that purpose. On the other hand, as will more fully appear hereinafter the stud 34 serves the dual 45 purpose of a stop on 10 or 11 engaging the flange 35 to limit the outward drop or opening movement, as well as a part to be engaged by a latch to prevent opening of the door from the outside, the purpose being 50 to so coördinate and arrange the parts as to eliminate the cumbersomeness, expensiveness, lack of neatness, and complexity prevalent in devices heretofore produced for this purpose. This flange 35 serves as a stop for 55 the pin 34 and limits the outward drop of the door, and as in the other features of construction the flange is made to serve not only as the fastening means for the face flange 8 or part of the outer frame but as 60 a practicably indestructible stop for the pin 34 which may be firmly and also unbreakably riveted into the side of the movable portion of the chute forming a part of the door. As the pin 34 is between the side 65 10 or 11 and the vertical side of the frame 4 it

offers no obstruction within the chute and is not exposed to breakage by coal being thrown against it. On the lower edge of the frame portion 5 is a pair of lugs 36 and 37 against which the upper edge of the 70 door rests in its closed position and on the bar 30 is a lug 38 which limits the downward movement of the lever 32.

Having thus described my invention I claim as new and desire to secure by Let- 75 ters Patent—

1. In a coal chute, a frame adapted to be inserted in a wall-opening, a door having segmental sides secured thereto and forming the sides of the outwardly projecting portion of the chute when open, and a stiffening rib having a flat side riveted to said door the ends of which are bent upon themselves and form trunnions which are revolvably mounted in the sides of said frame. 80

2. The combination with a frame 4 adapted to be inserted in a wall opening, of the frame portions 5, 6, 7 and 8 the portions 7 and 8 have each a flange 35 engaging the inner side or face of said frame 4 and also 90 adapted to serve as a stop, the door 9 having lugs 34 thereon each adapted to engage one of said stops to limit the opening movement of the door, a stiffening rib having 95 trunnion portions thereon upon which said door is pivotally movable, chute-portions or sides secured to and movable with said door, a shield 20 and a rod for supporting said shield pivotally and for supporting said sides relative to each other, and a latch 100 mechanism for locking said door.

3. The combination with a chute having the pivotally movable door 9 and frame 4, of the lever or handle 32 having a notch 33 therein, the sides 10 and 11 on said door, 105 and the stop pin or lug 34 on one of said sides to be engaged with said notch automatically when the door is closed and to engage said frame 4 when the door is open to limit its opening movement, said handle or lever having the incline 34' to be engaged by said pin to raise said handle or lever into engagement with said pin. 110

4. The combination with a frame 4 adapted to be inserted in a wall-opening 3 and 115 serving as a portion of a coal chute which is fixed, of a movable chute portion pivoted to said fixed portion and comprising a door 9 and sides 10 and 11, a stiffening rib 120 secured to form substantially an integral part of the lower edge of said door 9 the ends of which are bent to form the trunnions 16 and 17 mounted in said frame 4, a brace-bar 23 fixedly mounted in said sides 10 and 11, a wall-guard, or plate, 20 pivoted on said brace-bar, a bead portion 13 on the fixed portion of the chute projecting above the lower edge of said door 9 to form a closure against moisture entering under said door, a stop 35, means engaging said stop 125 130

to prevent accidental opening of the door and means engaging said stop to support the door in its open position, sides 10 and 11 which engage said stop to limit the opening 5 movement of said door and which engages said lever to hold said door locked in its closed position.

Copies of this patent may be obtained for five cents each, by addressing the "Commissioner of Patents.
Washington, D. C."

In testimony whereof I have hereunto set my hand in the presence of two subscribing witnesses.
